UNITED STATES PATENT OFFICE

148,041

DESIGN FOR A RADIO RECEIVER CABINET OR SIMILAR ARTICLE

Herbert J. Zeller, Jr., Dundee, Ill., assignor to
Stewart-Warner Corporation, Chicago, Ill., a
corporation of Virginia

Application September 21, 1946, Serial No. 133,478

Term of patent 14 years

(Cl. D56—4)

To all whom it may concern:

Be it known that I, Herbert J. Zeller, Jr., a citizen of the United States, residing at Dundee, in the county of Kane and State of Illinois, have invented a new, original, and ornamental Design for Radio Receiver Cabinet or Similar Article, of which the following is a specification, reference being had to the accompanying drawing, forming part thereof.

The figure is a perspective view of a radio receiver cabinet or similar article, showing my new design.

The characteristic features of my design reside in the portions shown by means of full lines in the drawing.

I claim:

The ornamental design for a radio receiver cabinet or similar article, substantially as shown and described.

HERBERT J. ZELLER, JR.
